UNITED STATES PATENT OFFICE

2,474,446

QUARTER BOOT FOR HORSES

Arthur E. Warren, Des Moines, Iowa

Application November 14, 1947, Serial No. 785,905

5 Claims. (Cl. 54—82)

1

This invention relates to an improvement in a quarter boot designed for use on the fore leg of a racing horse below the fetlock joint, to prevent injury to the front foot or losing of the shoe due to over reaching by the animal's rear foot.

The object of my invention is to provide a quarter boot of simple, durable and inexpensive construction which may be easily and quickly applied, and when so applied will be firmly held in place.

A further object of my invention is to provide an improved boot having its main body portion blanked from a single piece of leather and adapted to fit snugly around the foot and hoof with its outer surface smooth and free of projecting portions or obstructions.

A further object of my invention is to provide in that type of boot having a top body portion, and a bottom portion in the form of straps for shaping and holding the body portion in position to fit the foot; improved lining to cushion the body and to secure the straps in operative position.

My invention consists in the construction, arrangement and combination of the various parts of the device whereby the objects contemplated and attained as hereinafter more fully set forth, pointed out in my claims and illustrated in the accompanying drawings, in which:

Figure 1 is a side elevation of my improved boot and the manner that it is applied to a horse's front foot.

Figure 2 is a front elevation of the boot.

Figure 3 is a sectional view taken on the line 3—3 of Figure 2.

Figure 4 is an enlarged sectional view taken on the line 4—4 of Figure 3.

Figure 5 is a bottom view of Figure 1.

Figure 6 shows the body of the boot in blank.

Figure 7 shows the lining of the boot in blank.

Figure 8 shows the manner that the body and lining blanks are fastened together in the flat before being folded to its final form.

Referring to the drawing I have used the reference numeral 10 to designate the upper body portion of the boot and 11 the bottom portion of the boot. The top and bottom portions are stamped from a single piece of rectangular leather having a height of substantially one-third its length. The central portion 12 of the body is of a width and length of substantially one-fifth of the length of rectangular strip. The bottom edge of the blank is slightly curved inwardly at its central portion 13. The top edge of the body is also curved inwardly at its central portion 14 and

downwardly at its ends to form the top curved portion 16 inward to form wing portions 17 separated from the straps 18 of the bottom portion 11.

In Figure 7 I have illustrated the liner 19 which is also blanked from a single piece of soft leather such as pig skin. The liner is of a size and shape the same as the body with the exception that the upper edges 21 and 22 would extend beyond the edges of 14 and 16 of the body 10 when the said body is superimposed thereon. The liner 19 and body 10 are secured together by stitches 23. The edges 21 and 22 are doubled downwardly upon themselves, as illustrated at 24 Figure 4, to form a rounded edge 26, and to produce a cushion between the upper edge 14 and 16 of the body 10 and the skin of the horse's foot.

That portion of the lining opposite each of the wing portions 17 is provided with a diagonal pocket 27 formed by slackening the lining somewhat and securing in position by diagonal and spaced rows of stitches 28; the distance between the top row of stitches 28 being substantially one-half of the distance between the upper and lower edges of the wing 17 to give proper shape to the boot when formed. This is accomplished by threading the ends of the straps 18 through their corresponding loops 27 as illustrated in Figures 1, 2 and 3. A ring 29 is secured to the protruding end of one of the straps 18; a strap 31 and a buckle 32 is secured to the other end of said straps. A strip 33 is provided to reinforce the center of the lower body portion 11. A small wedgelike piece 34 is inserted between the strip 33 and the liner 19 to form a lug 36 to fit into the depression of the hoof when the boot is applied to the foot and hoof, the said lug providing means for centering the boot as it is applied and for preventing the slipping of the boot in either direction. The strap 31 is then placed around the front of the foot, thence through ring 29 and back to the buckle 32, thus providing means whereby the boot may be easily and quickly applied to foot and hoof, and when so applied be securely held in position.

By providing a liner of soft leather such as pig skin to cover the entire inner surface of the body with the upwardly extending portion 22 extending above the body 10, means is provided to prevent chafing of the horse's foot. By placing the straps 18 through the loops 27 and side of the wing portions 17, the wings are held firmly against the foot while the outer face of the body is free of any obstructions that might be engaged by the hind hoof by over reaching.

The main body portion and the strap portions 18, together with the corresponding portions of the liner 19, and also the reinforcing strip 33, are firmly stitched together while in the flat, thus providing easy and cheap construction. The ring 29, the strap 31 and the buckle 32 are attached after the straps 18 have been threaded through the pockets 27.

By glueing the wedge 34 between the strip 33 and the liner 19, a stabilizing lug 36 is firmly secured to the body portion 11, having a smooth inner surface to rigidly hold the boot in place and to prevent chafing. By placing the wedge 34 between the liner 19 and the strip 33, a very rigid stabilizing lug 36 is thus provided to firmly hold the boot against shifting around the horse's foot.

It will be seen that I have provided a quarter boot of simple, durable and inexpensive construction which may be easily and quickly applied, and when so applied will be firmly held in position.

I claim:

1. A quarter boot, comprising a central body portion having at each side of its upper end a lateral wing and at each side of its lower end a lateral strap-like portion formed of stiff material and a similar shaped liner formed of soft material superimposed on said body portions; a reinforcing strip supported on the lower body portion of the liner, including a central wedge like strip between the reinforcing strip and the liner, the liner including diagonal loops for receiving the ends of said strap-like portions when assembled, all of said portions being firmly stitched together to form a unitary structure.

2. A quarter boot, comprising a central body portion having at each side of its upper end a lateral wing and at each side of its lower end a lateral strap-like portion formed of stiff leather, and a similar shaped liner formed of soft leather superimposed on said body portions; the upper edge of said liner extending beyond the upper edge of said upper body portion to form a cushion for the upper edge of said body; a reinforcing strip on the lower body portion of the liner, including a central wedge between the reinforcing strip and the liner, the liner including diagonal loops for receiving the ends of said strap-like portions, all of said portions being firmly stitched together to form a unitary structure.

3. A quarter boot, comprising a central body

portion adapted to form a guard for the rear of the foot, circular wing portions projecting from the upper end of said body to encircle the sides of the foot, strap like portions projecting laterally from the lower end of said body, a liner covering the inner surface of said portions, that portion of the liner covering said wing portions including loops; said strap portions being threaded through the loops to give the boot the proper shape to fit the foot, and to draw and hold the wing portions firmly to the foot, the inner side of the lower end of said body having a reinforcing strip including a centering lug, a strap and buckle secured to one of said strap like portions and a ring secured to the end of the other one of said strap like portions.

4. A quarter boot, comprising an upper body portion to guard the sides of the foot and a strap like lower portion to protect the heel of the foot formed of a single piece of material; a liner covering the entire inner surface of said upper and lower body portions, a reinforcing strip inside of the central portion of the lining of the lower body portion and a wedge like lug between the lining and said reinforcing strip to form a stabilizing lug.

5. A quarter boot, comprising a central body portion adapted to form a guard for the rear of the foot, circular wing portions projecting from the upper end of said body to encircle the sides of the foot, strap like portions projecting laterally from the lower end of said body, a liner covering the inner surface of said portions, that portion of the liner covering said wing portions including loops; said strap portions being threaded through the loops to give the boot the proper shape to fit the foot, and to draw and hold the wing portions firmly to the foot, and means for detachably securing the ends of said strap like portions together.

ARTHUR E. WARREN.
